UNITED STATES PATENT OFFICE.

GEORGE E. RANDELLS, OF CLEVELAND, OHIO, ASSIGNOR, BY MESNE ASSIGNMENTS, TO THE FOOTE-BURT COMPANY, A CORPORATION OF OHIO.

WRINGER.

1,411,744.

Specification of Letters Patent.

Patented Apr. 4, 1922.

Application filed May 19, 1920. Serial No. 332,541.

To all whom it may concern:

Be it known that I, GEORGE E. RANDELLS, a citizen of the United States, residing at Cleveland, in the county of Cuyahoga, State 5 of Ohio, have invented certain new and useful Improvements in Wringers, of which the following is a specification.

The present invention relates to clothes wringers and more particularly to power 10 driven clothes wringers such as are used with power washing machines. In connection with the use of such wringers there is danger that the operator may accidentally get a finger or hand caught between the rolls 15 and in such case it is desirable to be able to quickly release the spring pressure on the rolls. Also it may sometimes be desirable to be able to quickly release the rolls in case clothes or other articles being wrung get 20 wound around the rolls. For this purpose there are in use what are termed quick release mechanisms for wringers and the object of my present invention is to provide an improved structure and arrangement in a 25 mechanism of this character.

For a consideration of what I believe to be novel and my invention, attention is directed to the accompanying description and the claims appended thereto.

30 In the drawing, Fig. 1 is a side elevation of the upper part of a wringer embodying my invention, the wringer frame being broken away for purposes of illustration; Fig. 2 is a side elevation of a part of the 35 quick release mechanism with parts broken away for purposes of illustration. Fig. 3 is a sectional view taken on line 3—3 of Fig. 2; Figs. 4 and 5 are side and end views of a modification, and Fig. 6 shows a complete 40 wringer.

Referring to the drawing, 10 indicates the frame of a wringer, 11 the rolls, and 12 a gear box in which is a gearing shifted by handle 13 for starting, stopping and reversing 45 the rolls. The wringer is shown as being mounted on a post 14 so that it can swing in a horizontal plane. The ends of the rolls have stub shafts which are carried in suitable bearings in the sides of the frame as is 50 well understood and extending across the frame is a flat spring bar 15 the ends of which rest on the upper wringer bearings for forcing the rolls together. Connected to the center of bar 15 by means of a swivel 55 connection 16 is a threaded post 17 having

an operating handle 18 on its upper end. As is well understood when post 17 is screwed down spring bar 15 will force rolls 11 together while when it is screwed up it will relieve the tension on the rolls. 60

Now according to my invention, I provide a two part or split nut in which post 17 screws and arrange my mechanism so that the two parts of the nut are normally held together in engagement with post 17 but 65 may be instantly released and permitted to move apart to release post 17 thereby releasing spring bar 15 and hence the pressure on rolls 11. The arrangement is also such that there is a releasing handle or knob 70 at each end of the wringer so there is always one in a convenient position for the operator.

The split nut is arranged directly beneath the top wall of the wringer frame and comprises two parts 20 and 21. The part 20 is 75 carried upon the upper end of a short vertical arm 22 which is pivoted at its lower end on a shaft 23 the ends of which are carried in the wringer frame, and such nut part is biased to a position where its threads are in 80 engagement with those on post 17 by a weight 24 carried on the end of an arm 25 which is connected to and extends at a right angle to arm 22. Preferably nut part 20, arm 22, arm 25 and weight 24 are formed as 85 an integral structure, being made, for example, as a single casting. In a similar manner nut part 21 is carried on the upper end of a short, vertical arm 26 which is pivoted at its lower end on a shaft 27 the ends 90 of which are carried in the wringer frame, and such nut part is biased to a position in engagement with the threads on post 17 by a weight 28 carried on the end of an arm 29 which is connected to and extends at a right 95 angle to arm 22. Nut part 21, arm 26, arm 29 and weight 28 may also be made as a single casting. The two nut parts are thus biased by the weights to positions where they engage the threads on post 17 and in order 100 to positively hold them in such positions, I provide a latch comprising a rectangular frame 30 which at one end is pivoted by a pin 31 to ears 32 on the upper end of nut part 21. The other end of frame 30 fits over 105 nut part 20 as best shown in Fig. 2, and thus serves to keep the nut parts from separating. Fastened on nut part 20 and in the end of frame 30 are wear pieces 33 and 34 which may be made of steel for example, and which 110

serve to protect latch 30 against wear. Connected to frame 30 are two extensions 35 and 36, extension 35 being heavier than extension 36 so that it serves to bias latch frame 30 into a position over the end of nut part 20 and to hold the end of extension 36 against a head 37 on the inner end of a pin 38. Pin 38 extends through the top of the wringer frame and has a knob 39 on its outer end. Extending through the top of the wringer frame at its other end is a pin 40 having a knob 41 on its outer end and a head 42 on its inner end which head rests on one end of a short lever 43. Lever 43 is pivoted in the wringer frame at 44 and its other end is located under the end of extension 35. Latch frame 30, and extensions 35 and 36 may be considered as being a continuous latch or locking lever pivoted on nut part 21 and as is obvious if either knob 39 or knob 41 is pushed inward, such lever will be turned on its pivot to release the latch moving it from over the end of nut part 20. In the case of knob 39 the action on the lever 25 is direct while in the case of knob 41 the action takes place through lever 43.

When the nut parts are in the positions shown in the drawing, being locked together by the latch frame 30, post 17 may be 30 screwed up and down at will to decrease and increase the tension of spring bar 15 on the rolls 11. Assume that post 17 is screwed down so that spring bar 15 is under tension and it is desired to quickly release such tension. To do this the operator has merely to push on either knob 39 or knob 41 when the latch lever will be moved off nut part 20 as already explained, and the upward pressure of spring bar 15 on post 17 will instantly 40 move the post upward to release rolls 11, the nut parts being forced apart against the action of weights 24 and 28 by the threads on post 17. That is, the upward pressure of the threads on post 17 against the threads on the 45 parts of the nut will cause the parts of the nuts to spread so the post can slide past them.

As soon as the pressure on rolls 11 is relieved, post 17 will come to rest and weights 50 24 and 28 will bring the nut parts into engagement with it. If the threads on the nut parts register with and strike into those on the post, then the weighted extension 35 will bring the latch frame 30 down over nut part 20 to again lock the nut parts together. On the other hand, if the threads do not 55 strike into each other, as soon as post 17 is turned to screw it down or up, the threads will immediately come into engagement whereupon the latch will fall into locking 60 position. It will thus be seen that the resetting of the quick release mechanism is entirely automatic, requiring no extra operation on the part of the operator.

65 Instead of utilizing weights for biasing

the nut parts into engagement with the post 17, I may use other suitable means and in Figs. 4 and 5 I have shown a modification wherein the biasing means is in the form of a spring. In these figures, 20^a and 21^a indicate nut parts, corresponding to nut parts 20 and 21, Fig. 1, which are carried on the upper ends of short, vertical arms 22^a and 26^a pivoted on shafts 23^a and 27^a. Coiled around shafts 23^a and 27^a is the central part 70 of a spring 45, the two ends of which engage nut parts 20^a and 21^a to force them together and into engagement with the threaded post. 75

As will be clear, a quick release mechanism made in accordance with my invention is 80 simple in structure, requiring but few parts, none of which must be accurately dimensioned or fitted which makes for low cost in manufacturing and ease in assembling. At the same time the arrangement is positive 85 in operation and not likely to get out of order. This latter is of prime importance for while the quick release mechanism may be called upon to operate but seldom, when it is called upon, the operation wants to be sure 90 and positive. To lift or turn the latch lever requires but a small amount of pressure applied to either knob so that the release of the wringer rolls may be accomplished almost instantly. It is also advantageous to have 95 the mechanism operated by a push on the lever as this does not require taking hold of them but merely pushing on them, a thing which can be done in the shortest space of time; and by having a knob at each end of 100 the wringer, there is always one directly adjacent the operator for instant operation.

Post 17 passes freely through the opening in the top wall of the wringer frame and the threads on it and on the nut parts are of 105 suitable V-shape of such an angle that the upward thrust of post 17 tends to spread the nuts. The opening in frame 10 through which post 17 passes is provided with a flange surrounding it and this forms a guide 110 for such post so that when it is released from between the nut parts it is held vertical and guided in its movements. This is important in the quick release of the wringer as it keeps the post from moving sideways with either 115 nut part thus insuring the quick and simultaneous disengagement of the nut parts from the post.

In accordance with the provisions of the 120 patent statutes, I have described the principle of operation of my invention, together with the apparatus which I now consider to represent the best embodiment thereof, but I desire to have it understood that the apparatus shown is only illustrative and that the 125 invention may be carried out by other means.

What I claim as new and desire to secure by Letters Patent of the United States, is:

1. In a wringer, the combination of a 130 frame, rolls, a threaded post for increasing

- and decreasing the tension on said rolls, a nut for the post comprising a plurality of parts, means biasing said nut parts to positions in engagement with the threads on said 5 post, means for holding the nut parts in such positions, and means for releasing said holding means, whereby tension on the rolls may cause the post to spread the nut parts thereby releasing the post and permitting it to 10 move upwardly to relieve the tension on the rolls.
2. In a wringer, the combination of a frame, rolls, a threaded post which passes through the frame for increasing and decreasing the tension on said rolls, a nut for the 15 post comprising a plurality of parts, arms pivotally supported on the frame which carry said nut parts, said arms being biased to positions where said nut parts are 20 in engagement with the threads on said post, locking means for said arms, and means for releasing said locking means, whereby tension on the rolls may cause the post to spread the nut parts thereby releasing the post and 25 permitting it to move upwardly to relieve the tension on the rolls.
3. In a wringer, the combination of a frame, rolls, a threaded post for increasing and decreasing the tension on said rolls, a 30 pair of arms pivoted at one end between the sides of the wringer frame, nut parts carried by the other ends of said arms, said nut parts being adapted to engage the post, upward pressure on the post caused by tension 35 on the rolls acting to automatically spread the nut parts by turning the arms on their pivots, means for latching the nut parts in positions where they engage the threads on said post, and means projecting beyond the 40 wringer frame for releasing said latching means.
4. In a wringer, a frame, rolls carried by the frame, a threaded post for increasing and decreasing the tension on said rolls, arms 45 pivotally supported on the frame, nut parts carried thereby adapted to engage the threads on said post, a latch pivoted on one of said arms for locking said nut parts together with their threads in engagement 50 with the threads on said post, and means operable from outside the wringer frame for releasing said latch, whereby tension on the rolls may cause the post to spread the nut parts thereby releasing the post and permitting it to move upwardly to relieve the tension 55 on the rolls.
5. In a wringer, a frame, rolls carried by the frame, a threaded post for increasing and decreasing the tension on said rolls, pivoted arms, nut parts carried thereby, means biasing said arms to positions where said nut parts are in engagement with the threads on said post, a latch pivoted on one of said 60 arms for latching said nut parts together, and means operable from outside the wringer 65 frame for releasing said latch, whereby tension on the rolls may cause the post to spread the nut parts thereby releasing the post and permitting it to move upwardly to relieve the tension on the rolls.
6. In a wringer, the combination of rolls, a threaded post for increasing and decreasing the tension on said rolls, a nut for the post comprising a plurality of parts, pivoted arms which carry said nut parts, a lever for locking said nut parts in positions 70 where they engage the threads on said post, said lever extending approximately the length of the wringer frame, and means at each end of the wringer frame for moving said lever to release said parts.
7. In a wringer, the combination of rolls, a threaded post for increasing and decreasing the tension on said rolls, a nut for the post comprising a plurality of parts, latching means for locking said nut parts in engagement with the threads on said post, means biasing said latching means to locking position, and means operable from outside the wringer frame for moving said 80 latching means against the biasing force to release the nut parts, whereby tension on the rolls may cause the post to spread the nut parts thereby releasing the post and permitting it to move upwardly to relieve the tension on the rolls.
8. In a wringer, the combination of rolls, a threaded post for increasing and decreasing the tension on said rolls, a nut for the post comprising a plurality of parts, said 85 parts being biased to positions where they are in engagement with the threads on said post, latching means for locking said nut parts in engagement with the threads on said post, said latching means being biased to locking position, and means operable from outside the wringer frame for moving said latching means against the biasing force to release the nut parts.
9. In a wringer, the combination of a frame, rolls, a threaded post for increasing and decreasing the tension on said rolls, a nut for the post comprising two parts, arms pivotally supported on the frame upon which said nut parts are carried, means 100 biasing said nut parts toward positions where they engage the threads on said post, a locking member pivoted on one of said nut parts and adapted to engage the other to lock them together, said locking member being biased to locked position, and means operable from outside the wringer frame for moving said locking member to release the nut parts, whereby tension on the rolls may cause the post to spread the nut parts thereby releasing the post and permitting it to move upwardly to relieve the tension on the rolls.
10. In a wringer, the combination of a frame, rolls, a threaded post for increasing 115

- and decreasing the tension on said rolls, a vertically projecting arm which is pivoted at its lower end on the frame, a nut member carried by the upper end of said arm 5 and adapted to engage the threads on the post, upward pressure on the post acting to automatically turn the arm on its pivot to move the nut member from engagement with the post, a latch for locking the nut member 10 in engagement with the threads on the post, and means operable from outside the wringer frame for moving said latch to release the nut member.
11. The combination with a wringer comprising a frame, rolls, tension means for the rolls, and a screw for increasing and decreasing the pressure exerted by the means on the rolls, of a divided nut, the parts of which are 15 hinged to the frame on opposite sides of the screw, a member which co-operates with the 20 hinge pivots to hold the parts of the nut in engagement with the screw, and a device for moving the member in a direction to release the parts of the nut.
12. The combination with a wringer comprising a frame, rolls, tension means for the rolls, and a screw for increasing and decreasing the pressure exerted by the means on the rolls, of a nut comprising members which are hinged to the frame, and normally engage the screw, said tension means causing the parts of the nut to separate when they are released, a device for normally locking the parts of the nut, and means causing the parts of the nut to automatically re-en- 25 gage the screw after each release of the screw and tension means.
13. The combination with a wringer comprising a frame, rolls, tension means for the rolls, and a screw for increasing and decreasing the pressure exerted by the means on the rolls, of a divided nut, the parts of which are hinged to the frame on opposite sides of the screw, a member which co-operates with the 30 hinge pivots to hold the parts of the nut in engagement with the screw, and a device for moving the member in a direction to release the parts of the nut.
14. The combination with a wringer comprising a frame, rolls, tension means for the rolls, and a screw for increasing and decreasing the pressure exerted by the means on the rolls, of a nut comprising members which are hinged to the frame, and normally engage the screw, said tension means causing the parts of the nut to separate when they are released, a device for normally locking the parts of the nut, and means causing the parts of the nut to automatically re-en- 35 gage the screw after each release of the screw and tension means.

In witness whereof, I have hereunto set my hand this 13th day of May, 1920.

GEORGE E. RANDLES.
